TOY

Application filed April 25, 1928. Serial No. 272,595.

This invention relates to toys, and has for an object the provision of a miniature airplane adapted to be forcibly ejected into flight from a tube, by air pressure.

Another object is the provision of a toy of the general character described, which is so designed and proportioned that it may be ejected from the tube with sufficient velocity to fly for a considerable distance, even though relatively low pressure is employed, so that the toy can be operated by simply placing one end of the tube to the mouth and blowing therethrough.

Another object is the provision of a miniature airplane receivable within a tube, to be ejected therefrom by air pressure, and which is provided with wings foldable to be accommodated within the tube, and with means for extending the wings to flying position when released from the tube.

Another object is the provision of a toy as above described, which is of simple construction and which may be inexpensively manufactured, which will result in imparting to the toy a decided advantage as an advertising medium.

Another object is the provision of a toy as described, which, while being of very simple construction and easily operated, is sufficiently strong and durable to withstand a certain degree of the hard usage to which it would be subjected in the hands of children.

The invention possesses other objects and features of advantage, some of which, with the foregoing, will be set forth in the following description of the preferred form of the invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings:

Figure 1 is a perspective view disclosing the manner of operating the toy of the present invention.

Fig. 2 is a top plan view of the miniature airplane forming a portion of the toy, and

showing it with its wings extended for flying position.

Fig. 3 is a side elevation, the direction of view being indicated by the arrow 3 of Fig. 2.

Fig. 4 is a longitudinal, vertical sectional view of the ejector tube, and showing the miniature airplane in side elevation therein, with its wings in folded position.

Fig. 5 is a longitudinal, horizontal sectional view of the tube, and showing the airplane with its folded wings in plan view.

Fig. 6 is a transverse, vertical sectional view, the plane of section being taken upon the line 6—6 of Fig. 4, with the direction of view indicated by the arrows.

Broadly considered, the toy of the present invention comprises a tube, and a miniature airplane slidably receivable within the tube and adapted to be ejected therefrom by air pressure.

Specifically describing the present embodiment of the invention, the toy comprises a blower tube 6 which may be composed of any suitable material such as cardboard, and which is preferably of such proportions that it may be readily applied to the mouth of a child or other operator for the purpose of blowing the breath therethrough.

A folding miniature airplane indicated in its entirety at 7, is provided, and is of such dimensions that it is slidably receivable within the tube 6. The miniature airplane 7 comprises a body 8 corresponding to the fuselage of a real airplane, to which preferably a pair of wings 9 is pivoted at their inner ends by means of any suitable pivot pin such as a relatively large headed tack 11, the shank 12 of which extends rigidly and vertically through the body 8 and serves as a pivot for both of the wings 9.

Preferably a single elastic band 13 is secured at each end to one of the wings 9 at a point 14 spaced from the pivot pin 12 with the center 16 of the band 13 extending over and secured to the forward end 17 of the body 8. Any suitable means for attaching the ends of the band 13 to the wings 9 may be employed, but I have found a convenient and inexpensive means for accomplishing this end, to be the conventional gummed stickers.

18, which may have their gummed surfaces moistened and then be pressed upon a surface of one of the wings with the end of the elastic band 13 positioned thereunder. When sufficient time has elapsed for the gum to dry, it will be found that the ends of the band 13 are securely fastened to the wings.

In securing the ends of the band 13 to the wings 9, the band 13 should be sufficiently tensioned so that the wings 9 are normally urged to a position wherein they extend laterally from the body 8. This is their flying position and is indicated in Fig. 2. A notch 19 is provided in the leading edge of each of the wings 9, and another notch 21 is provided in the body 8 aft of the pivot pin 12. A cord 22 of suitable length is provided with a knot 23 at each end, and the cord 22 then has an end engaged within each of the notches 19, and the center of the cord engaged within the notch 21. The knots 23 serve to prevent displacement of the cord 22 from the notches 19, and the notch 21 is formed to slope downwards and forwards of the body 8 so that the normal tension of the cord, while it is serving to limit the action of the elastic band 13 to hold the wings 9 in flying position, will tend to retain the center portion of the cord 22 within the notch 21.

30 A conical flange or head 26 is secured to the forward end or nose 17 of the body 8, preferably over a portion of the elastic band 13. The nose 17 of the body 8 may be pointed if desired, to provide a firmer seat for the conical flange 26 which flares backwards therefrom and is so proportioned that the diameter of its after end or base 27, establishes a sliding fit within the tube 6, as shown in Figs. 4, 5, and 6. One or more vanes 28 are carried at the after end of the body 8 to serve as steering rudders to guide and control the flight of the miniature airplane 7 through the air; it being understood of course, that both the vane or vanes 28 and the wings 9 are slightly less in width than the inside diameter of the tube 6, so that the airplane 7 may be slidably received therein when the wings 9 are folded back to extend longitudinally of the body 8. Preferably the vane or vanes 28 are formed of relatively stiff material such as cardboard, so that it may be bent to any desired configuration, within limits, and remain as adjusted.

55 The conical flange 26 may also be composed of thin cardboard; and the body 8 and wings 9 are preferably formed of light, thin wood.

The manner of operating my improved toy is substantially as follows:

The airplane 7 is first thrust nose first into 60 one end of the tube 6. As the airplane 7 is pushed into the tube 6, the leading edges of the wings 9 will engage the ends of the tube and cause the wings 9 to be folded back to a position wherein they extend longitudinally 65 of the body 8 to permit the airplane 7 to be

received within the tube 6. Then, by placing the same end of the tube as that through which the airplane 7 was thrust, to his mouth, the operator may blow through the tube; and it will be found that the pressure thus developed in the tube behind the conical flange 26, will eject the airplane 7 from the tube with sufficient velocity to sail through the air for a considerable distance. This sailing action is enhanced by the wings 9, which, immediately upon their passing the outer end of the tube 6 to be released thereby, are snapped into flying position by the elastic band 13.

70 It should be understood that I do not wish to be limited to the specific construction of the miniature airplane herein described, but that various changes in the general design thereof may be made without departing from the spirit and scope of the subjoined claim.

75 Another variation from the above described structure which is capable of being performed without departing from the scope of the present invention, is to provide the blower tube 6 with any kind of whistle or other instrument capable of producing noise 80 when air is forced therethrough, such as the ordinary toy siren universally upon the market. Such a siren could be positioned within one end of the tube to function simultaneously with the ejection of the miniature 85 airplane 7 from the blower tube 6 when the operator blows therethrough. This feature would considerably enhance the appeal of the toy to most children, because of the close 90 simulation of the warning siren which is sounded at many aviation fields when a flight 95 is about to start. However, the type of tube previously described wherein no whistle is employed, is preferable, because of the fact 100 that the inclusion of the whistle would necessitate inserting the miniature airplane 7 into the tube backwards from the outer end of the tube 6. This would require that the wings 9 be first folded back manually; and because 105 of the difficulty which might be encountered in inserting the conical flange 26 backwards into the tube, the toy would be more liable to damage in the hands of a child.

110 The toy of the present invention may be constructed very cheaply, and therefore 115 would be highly desirable as an advertising medium. Any desired subject matter might be printed or otherwise affixed to the outside of the blower tube 6, and because of the inherent appeal of such a toy to children, a wide 120 circulation of this subject matter throughout the surrounding community could be attained by any business house distributing the toys among the children of its patrons.

115 I claim:

A toy comprising in combination a tube, a 125 miniature airplane slidable within said tube, said airplane being adapted to be ejected from the tube by air pressure and comprising a body, wings pivoted to said body to 130

permit their being optionally folded to extend longitudinally of the body or extended laterally therefrom when released by the tube, resilient means urging the wings to 5 extended position, a flexible cord secured at one end to said body and at the other end to each of said wings to limit the action of said resilient means, a conical flange extending from said body to engage the sides of the 10 tube and establish a sliding and substantially air-tight seal therewith, and a vane carried by said body to serve as a flight-controlling rudder.

In testimony whereof I have signed my 15 name to this specification.

ADRIANO A. BISSIRI.
